FIG. 1

FIG. 2

William P. Hammond

INVENTOR.

UNITED STATES PATENT OFFICE.

WILLIAM P. HAMMOND, OF PASSAIC, NEW JERSEY.

DESIGN FOR AN AUTOMOBILE-BODY.

49,798.

Specification for Design.

Patented Oct. 24, 1916.

Application filed August 12, 1915. Serial No. 45,255. Term of patent 7 years.

To all whom it may concern:

Be it known that I, WILLIAM P. HAMMOND, a citizen of the United States, residing at Passaic, in the county of Passaic and State of New Jersey, have invented a new, original, and ornamental Design for Automobile-Bodies, of which the following is a specification, reference being had to the accompanying drawing, forming a part thereof.

Figure 1 is a top plan view of an automobile body showing my new design. Fig. 2 is a view thereof in side elevation.

The automobile body illustrated is provided with a seating compartment substantially the width of the widest part of the body, the outside portion of the body forming the seating compartment being in the same vertical plane with the outer edges of the fenders or mud guards, as is plainly shown in Fig. 2. The increased width of the seating compartment is made possible

by the omission of the conventional running-board and the extension of the intermediate portion of the body outwardly on each side in line with the edges of the mud-guards or fenders, the latter projecting forwardly and rearwardly and being interrupted by said body. The fenders, as shown, preferably merge into the body to produce the well-known and desirable stream line effect.

In my design the rear end of the body is formed with an ogee-like curve with a lower portion thereof slightly scalloped to conform to the general contour of the adjacent portion of the wheel and in order to accommodate said wheel if found desirable.

I claim:

The ornamental design for an automobile body as shown and described.

In testimony whereof I have hereunto set my hand.

WILLIAM P. HAMMOND.
